MANICURING IMPLEMENT

Filed May 31, 1945

UNITED STATES PATENT OFFICE

2,422,207

MANICURING IMPLEMENT

Rebecca Nalpantian, San Francisco, Calif.

Application May 31, 1945, Serial No. 596,893

2 Claims. (Cl. 132—75.5)

1

This invention relates to cutlery and has for its object to provide a combined cuticle pusher and nippers.

Another object of the invention is to provide a manicuring device comprising a pair of lever actuated cuticle pushers.

A further object of the invention is to provide a combination lever operated pair of nippers and cuticle pushers.

A still further object of my invention is to provide a combined nipper and cuticle pusher operated by scissor action.

Other features and advantages will become more readily apparent from the following description and the accompanying illustrative drawings in which:

Figure 1 is a plan view of one form of my invention.

Figure 2 is an enlarged view similar to Figure 1, showing the device in operative position.

Figure 3 is a view similar to Figure 1, illustrating a modification, and

Figure 4 is another plan view showing a still further modification.

In the accompanying drawings as above enumerated and in the following specification, like characters of reference indicate like parts throughout and in which 10, indicates my manicuring implement, which comprises a pair of cuticle pushers 11 and 12, the two forming the approximate shape of the inner portion of a fingernail and each of which is secured to the ends 13 and 14, of shanks 15 and 16, spread apart at 17 and 18, and pivotally connected together at 19. From the point 19, the shanks flare away from one another as at 20 and 21, terminating in rings 22 and 23. The outer edges 24 and 25, of the members 11 and 12, form nippers for removing small pieces of cuticle. In operation, the manicurist engages the rings 22 and 23, with her fingers and places the bottom edges 26 and 27, against the cuticle of the fingernail and spreads said rings apart, whereby said edges will spread away from one another, shoving the cuticle of the nail downwardly and outwardly. The members 11 and 12, are segmental and somewhat concave in form as indicated in Figure 2.

In Figure 3, I show a modification of the invention wherein the straight shanks 28 and 29, do not cross one another at the pivotal point as at 30. The outer ends of these shanks form nippers 31 and 32, and the edges 33 and 34, form the cuticle pushers and the rings 35 and 36 spread

2

apart when the edges 31 and 32, are in contact. In this case the rings 35 and 36, must be drawn together to spread the pusher edges 33 and 34, apart.

5 In Figure 4, I show another modification in which the cuticle pushers 37 and 38, are semi-ovals of slightly inclined upright form and the free ends 39 and 40, of which terminate in substantially razor edges 41 and 42.

10 It is thought that persons skilled in the art to which the invention relates will be able to obtain a clear understanding of the invention after considering the description in connection with the drawings. Therefore, a more lengthy description 15 is regarded as unnecessary.

Minor changes in shape, size and rearrangement of details and parts such as come within the purview of the invention claimed may be resorted to, in actual practice, if desired.

20 Having now described my invention that which I claim as new and desire to procure by Letters Patent is:

1. In a manicure instrument a pair of scissor action levers, a finger receiving ring at one end 25 of each lever, a cuticle pushing jaw on each of the opposite ends of the levers, said jaws lying in opposed relation and being movable toward or away from one another in the same plane, a curved outer edge on each jaw to engage and push back the cuticle on the finger of the user, each jaw being relieved along its inner edge and cutting edges at the extreme outer ends of the jaws forming nippers for clipping loosened cuticle.

2. In a manicure instrument, a pair of shanks 35 having cooperative cuticle pushing jaws mounted upon the front ends thereof and being connected at their rear ends, the jaws lying in opposed relation and being movable toward and away from one another in the same plane, a curved 40 outer edge on each jaw to engage and push back the cuticle on the finger of the user, each jaw being relieved along its inner edge, and cutting edges at the extreme outer ends of the jaws forming nippers for clipping loosened cuticle.

45 REBECCA NALPANTIAN.
